(57) CLAIM

The ornamental design for a baby carrier, as shown and described.

DESCRIPTION

FIG. 1 is a perspective view of a baby carrier, showing my new design;

FIG. 2 is a front view of the baby carrier of FIG. 1;

FIG. 3 is a rear view of the baby carrier of FIG. 1;

FIG. 4 is a left side view of the baby carrier of FIG. 1, the right side view being a mirror image thereof;

FIG. 5 is a top view of the baby carrier of FIG. 1; and

FIG. 6 is a bottom view of the baby carrier of FIG. 1; and,

FIG. 7 is another perspective view of a baby carrier of FIG.

1 showing the baby carrier in a state of use.

The broken line showing of portions of the baby carrier is included for the purpose of illustrating environmental structure and forms no part of the claimed design.
